UNITED STATES PATENT OFFICE.

CHARLES H. LA BEEF, OF ONEIDA, NEW YORK.

BOTTLE-CAPPING MACHINE.

1,333,086.

Specification of Letters Patent.

Patented Mar. 9, 1920.

Application filed March 15, 1919. Serial No. 282,866.

To all whom it may concern:

Be it known that I, CHARLES HARRY LA BEEF, a citizen of the United States of America, and resident of Oneida, in the 5 county of Madison, in the State of New York, have invented new and useful Improvements in Bottle-Capping Machines, of which the following, taken in connection with the accompanying drawings, is a full, 10 clear, and exact description.

My invention relates to improvements in bottle capping machines, and it pertains to that class which is used for placing paper caps in the mouths of milk bottles and the 15 like.

Heretofore, as bottle capping machines have been constructed it often happens, in practical operation, that the caps do not pass readily through the horizontal opening at 20 the lower part of the magazine. This is caused by the varying thickness of the paper caps. They vary in thickness from one thousandth, (1/1000), to seventeen thousandths, (17/1000), of an inch.

25 As the machines are now made this opening at the lower part of the plunger cylinder can not be varied without taking the machine apart, or turning the screws which hold the bottom of the cylinder to the base 30 plate, and in no case can it be varied instantly.

This horizontal opening often becomes clogged on account of a cap being too thick to be completely passed or forced through 35 the opening, in which case the bottle is not capped and the machine becomes clogged, other caps being forced against the first one, the machine is prevented from working and liable to be badly injured. Much time is lost 40 in cleaning away the spoiled caps and putting the machine in order.

Again on account of the varying thickness or thinness of the caps it often happens that two very thin caps are forced into the opening 45 at once and become clogged.

My invention is intended to provide a method of instantly and automatically varying, or adjusting, vertically the size of the horizontal opening at the lower part of the 50 magazine, through which the caps have to be passed in order to be positioned under the plunger and over the mouth of the bottle to be capped, so it will correspond to the thickness or thinness of each cap as it is presented, 55 and adapted to allow only one cap to pass

through the opening at a time and also adapted to allow the thickest cap used to pass through without clogging.

I accomplish this purpose by having the opening made the approximate size that will 60 permit the entrance of the thickest cap used. Also, by somewhat elongating the plunger chamber either by cutting away that part of the wall or casting between the magazine and the cylinder, in those machines already 65 made, or by providing for it in new castings. In this chamber I place a device or member composed of suitable material as metal preferably, formed to fit the space between the magazine and the plunger, and which can 70 move up and down a short distance within the chamber as shown, the plane of each end of the device is rectangular; the planes of the top and bottom are perpendicular to the planes of the ends; the sides are concave. 75 One concave side of the device forms a part of the interior surface of the cap magazine; the other concave side forms part of the interior surface of the plunger cylinder. Holes are drilled lengthwise through the 80 casting, one on each side, through which supporting rods can be placed, one fastened to one end of the device and the other fastened to the other end. The upper part of these rods are supplied with tension spiral 85 springs and adjusting nuts so that the device can be held in equipoise, its lower surface is spaced approximately a sufficient distance from the bed plate on which the caps slide to allow the thinnest cap used to 90 enter the opening at the plunger cylinder. The device is never allowed to fall any lower.

In case a thicker cap is presented at the opening the moment it touches the balanced 95 device it, (the device), is instantly raised a sufficient distance to allow the thicker cap to enter the opening. We believe this is effected by the action of the tension springs. The device being held in equipoise the pressure of the cap as its upper surface touches the under surface of the device destroys the equipoise by releasing some of the weight of the device from the springs and the springs contract and raise the device just 100 a sufficient distance to restore the equipoise and allow the cap to completely enter the plunger chamber and become positioned under the plunger and over the mouth of 105 the bottle to be capped.

As soon as the cap is completely out from under the device its full weight is placed upon the tension springs and it falls to its original position. This action is repeated as rapidly as the caps can be presented. In that manner the opening is instantly and automatically varied to admit caps of varying thickness, varying from one thousandth to seventeen thousandths of an inch in thickness.

My invention is further explained by reference to the accompanying drawing, in which similar letters refer to similar parts throughout the several views.

Figure 1 is a vertical view of a part of the capping machine with my invention added.

Fig. 2 is another vertical section of a part of the capping machine with the addition 20 of my invention,

Fig. 3 is a plan view of a part of the machine looking at the bottom of the machine, with my invention in place.

Fig. 4 is a sectional view of the device 25 with the supporting rods and tension springs and regulating nuts.

Letter A represents the device. B represents the horizontal opening at the lower part of the magazine, it being the open 30 space between the bed plate on which the caps slide and the lower edge of the cylinder which is cut away one half of the circumference of the cylinder for a distance sufficient to leave room for the passage of the 35 thickest cap used. C represents the movable plate which is used to push the caps from the cap magazine into the cylinder and under the plunger. D represents the cap magazine, E the plunger cylinder, F the 40 plunger, G represents a cap partly in the magazine and partly in the plunger chamber. H represents the longitudinal hole in the casting through which a supporting rod K passes. L represents the spiral spring 45 at the upper end of the rod K and M the regulating nut on the end of the rod K. N represents a washer resting on the casting and surrounding the rod K and which acts as a shoulder on which rests the lower part 50 of the spiral spring L. O represents the hole in A into which the rod K is fastened by the nut P. Q represents caps in the magazine.

The operation of my invention is as follows:—When the device A is in its normal 55 position there is approximately room enough between its lower surface and the bed plate to allow the thinnest cap used to pass under it into the plunger cylinder. When the movable plate C pushes a thick cap from the magazine D so its edge is presented to the opening B its edge hits the lower edge of A and by its action and the action of the spiral springs L, A is raised upward a distance just sufficient to allow the cap to pass

under it and into the plunger cylinder. As the movable plate C is removed A falls to its first position and the opening B is ready to receive another cap. The action of A is instantaneous and automatic.

70

What I claim is:—

1. In a capping machine, the combination with a cap magazine having an opening through a wall thereof and a chamber containing a plunger of an equipoised device 75 partially closing the opening through the magazine wall.

2. In a capping machine, the combination with a cap magazine having an opening through a wall thereof and a chamber containing a plunger of a resiliently supported device partially closing the opening through the magazine wall.

3. The combination with a plunger chamber and a cap magazine having an opening 85 through the wall thereof permitting communication between the cap magazine and the plunger chamber of a substantially balanced device movable across said opening.

4. The combination with the plunger 90 chamber and the cap magazine having an opening through a wall thereof permitting communication between the cap magazine and the plunger chamber, said opening of a vertical width sufficient to permit the passage 95 of a cap of maximum thickness, of an equipoised device normally constricting said opening to a width permitting the passage only of a cap of practically minimum thickness.

5. The combination with the plunger chamber and the cap magazine having an opening through a wall thereof permitting communication between the cap magazine and the plunger chamber, said opening of a 105 vertical width sufficient to permit the passage of a cap of maximum thickness, of a spring supported substantially balanced device normally constricting said opening to a width permitting the passage only of a 110 cap of practically minimum thickness.

6. The combination with the plunger chamber and the cap magazine having an opening through a wall thereof permitting communication between the cap magazine 115 and the plunger chamber, said opening of a vertical width sufficient to permit the passage of a cap of maximum thickness, of a spring supported device between the plunger and the cap magazine and normally constricting said opening to a width permitting the passage only of a cap of practically 120 minimum thickness.

7. The combination with a cap magazine having an opening through a wall thereof 125 to permit the flatwise passage of caps of an equipoised movable device only partially closing said opening.

8. In a bottle capping machine, the combination with a cap magazine and a plunger 130

cylinder of a solid metal device with plane rectangular ends and each perpendicular side of the device concave to correspond to the concavity of the inside of the cap magazine and plunger cylinder respectively, with means for holding the device and for raising it a short distance within a chamber between the cap magazine and the plunger cylinder, made to receive it, and formed in the lower part of the casting which forms the body of the machine for the purposes as herein substantially described.

9. In a bottle capping machine, of the described class, the combination with a cap magazine and a plunger cylinder of a solid metal device with plane rectangular ends, the planes of the top and bottom perpendicular to the planes of the ends, each perpendicular side concave to correspond to the concavity of the interior surface of the cap magazine and plunger cylinder, respectively, and adapted to be contained in a chamber in the lower part of the body of the machine, situate between the cap magazine and the plunger cylinder, and means, independent of the other working parts of the machine, for holding said device in equipoise, and for raising and lowering it a short distance automatically and instantaneously to make the opening correspond to the thickness or thinness of each cap as the caps are successively presented at the

opening so that each cap can pass through the opening without clogging it.

10. In a capping machine, the combination with a cap magazine having an opening through the wall thereof and a chamber containing a plunger of an equipoised device arranged externally of the cap magazine and between the cap magazine and the plunger and normally partially closing the opening through the magazine wall.

11. In a capping machine, the combination with a cap magazine having an opening through the lower portion of a wall thereof and a chamber containing a plunger of a device spring supported from the upper wall of the plunger chamber so as to normally exist in an equipoised condition partially closing the opening through the wall of the cap magazine.

12. In a capping machine the combination with a cap magazine having an opening through a wall thereof and a chamber containing a plunger of a device partially closing the opening through the magazine wall and means for supporting said device in substantially balanced condition.

In witness whereof I have hereunto set my hand this 4th day of March, 1919.

CHAS. H. LA BEEF.
